IMPLEMENT HANDLE

Albert Alfred MacPherson, Five Dock, near
Sydney, New South Wales, AustraliaApplication September 12, 1935, Serial No. 40,340
In Australia June 6, 1934

5 Claims. (Cl. 273—75).

This invention relates to implements of all kinds that are provided with handles to enable the implement to be wielded manually for working or recreation purposes. Instances of such implements are hammers, tennis rackets, golf clubs, cricket bats etc.

In such implements it is found that users require a certain "balance" of the implement that is to say the centre of gravity of the implement must be at a definite distance from the user's hand for efficient and untiring use.

Now this invention has been devised to enable the centre of gravity of such implements to be adjusted as required. This desiderata being effected by providing an axial recess within the handle wherein a weight is housed having devices to adjust its position longitudinally of said recess and devices to retain said weight in any such adjusted position.

20 But in order that this invention may be readily carried into practical effect it will now be described with reference to the drawing wherein Fig. 1 is a sectional elevation of one end of an implement handle. Fig. 2 is a section on line 25 2—2 in Fig. 1. Fig. 3 is a similar view to Fig. 1 showing a modified embodiment of the invention. Fig. 4 is a section on line 4—4 in Fig. 3 and Fig. 5 is a similar view to Figs. 1 and 3 of a further embodiment of the invention.

30 Referring to Figs. 1 and 2 the handle 6 has axial recess 7 which is counterbored as shown at 8. Within the counterbore is a plug 9 providing end support for keys or runner guides 10 which are supported at their other ends in the bottom 11 of the recess 7. A weight 12 has grooves 13 to engage the guides 10 and said weight is medially screwed for a lead screw 14 having bearing in the plug 9 and a slotted head 15. A spring washer 16 is interposed between 35 the plug 9 and the head 15 and the thrust of said washer is counteracted by an annular abutment disc 17 affixed to the end of the handle by screws or the like (not shown).

In use the weight 12 is adjusted longitudinally 40 by rotation of the screw 14 and is retained in such position by the thrust of the spring washer 16 preventing rotation of said screw 14. Referring to Figs. 3 and 4 the handle 18 has recess 19, plug 20 and pad 23 of felt or the like and guides 21. The weight 22 has grooves for the guides 21 and as well has end flanges 24 between which is retained a sleeve 25 of rubber or the like which resiliently grips the outer sides of the guides 21 and the weight 22. The weight 55 22 has one end countersunk and provided with

screwed orifice 26 intended to receive the screwed end 27 of a thrust rod 28 which loosely fits orifice 29 in the plug 20.

In use the weight 22 is adjusted longitudinally by screwing the end 27 of the thrust rod 28 into orifice 26 and thrusting or pulling said rod 28 until the weight is in the desired position. The weight 22 is retained in position by the sleeve 25 gripping on the guides 21.

Referring to Fig. 5 the handle 30 has recess 31 plug 32 and a pad 33. The weight 34 has end flanges 35 between which is retained a rubber or like sleeve 36 which neatly fits the recess 31. In use the weight is moved as previously described in connection with Figs. 3 and 4 and is 15 prevented from moving of its own accord by the neat fit of the sleeve 36 in the recess 31.

It will be observed with respect to the Figs. 3 and 5 embodiments of the invention that they disclose different mechanical embodiments of 20 the generic idea of employing a resilient friction member resiliently engaging means extending longitudinally of the handle to hold the weight in any position to which it may be forcibly adjusted along the bore, thereby permitting the use 25 of an adjusting member which is normally disengaged from the weight and which is engaged therewith only when an adjustment is desired. In the Fig. 3 form of the invention the means extending longitudinally of the handle and engaged by the friction member are the rods 21, 30 while in the Fig. 5 form it is the wall of the bore 31.

I claim:

1. An implement having a handle provided with a bore extending longitudinally thereof, a weight within said bore having means to be detachably engaged by a member for forcibly adjusting the same along the bore, a member of resilient friction material carried by the weight 40 and held against longitudinal movement relative thereto, and means extending along the handle and resiliently and frictionally engaged by said member to hold the weight against accidental longitudinal movement along the bore 45 from any position to which it may be forcibly adjusted by said adjusting member.

2. The combination as set forth in claim 1 in which the means extending longitudinally along the bore and frictionally engaged by the resilient 50 member comprises a rod which extends through the weight and holds the weight against rotation.

3. The combination as set forth in claim 1 in which the means extending longitudinally 55

along the bore and frictionally engaged by the resilient member comprises a rod extending through the weight and exposed at the side thereof, and in which the friction member is in the form of a sleeve embracing the weight and contractively engaging the rod.

4. An implement having a handle provided with a bore extending longitudinally thereof, a weight within said bore adjustable therewith and having means to be detachably engaged by a member for adjusting the weight along the

bore, and a member of resilient friction material carried by the weight and held against longitudinal movement relative thereto and expansively engaging the wall of the bore to hold the weight against longitudinal movement along the bore from any position to which it may be adjusted by said adjusting member.

5. The combination as set forth in claim 4 in which the resilient friction member is in the form of a sleeve surrounding the weight.

ALBERT ALFRED MacPHERSON.
